Martin Jachimow
ATTORNEY

UNITED STATES PATENT OFFICE

HARRY HERTZBERG, OF BROOKLYN, NEW YORK, ASSIGNOR TO HERTZBERG PATENTS INC., OF NEW YORK, N. Y., A CORPORATION OF NEW YORK

SQUEEGEE MOP

Application filed September 5, 1929. Serial No. 380,609.

This invention relates to wet mops and more particularly to that type of such mops which are intended for cleaning floors and provided with means to wring water out of the mop material.

It is the object of this invention to provide a mop of this type which is particularly adapted for cleaning tiled or terazzo floors and which for this purpose is equipped with special means for collecting water on a floor which will be absorbed by the mop material surrounding these means in one operation.

With this and other objects in view the invention consists in certain novel features of construction, combination of elements and arrangements of parts which will be more fully described in these specifications and finally pointed out in the appended claims.

The invention is shown in the accompanying drawing which forms a material part of these specifications and in which:

Fig. 1 is a perspective elevation of my squeegee mop with mop cords stretched and the squeegee plate in operating position.

Fig. 2 is a perspective elevation of the same mop in collapsed position for mopping a floor or the like.

Fig. 3 is a perspective view of the same mop in collapsed position when in use for simultaneous use of squeegee and mop.

Fig. 4 is a plan of the mop head in the position of Fig. 3, the arrows indicate the flow of water to the mop material when the mop is pushed forward.

Fig. 5 is a perspective view of the mop when stretched and twisted for wringing water from the mop material.

Fig. 6 is a detail side elevation of the mop head partly in section on line 6-6 of Fig. 7.

Fig. 7 is a detail front elevation of the mop head, partly in section on line 7-7 of Fig. 6.

Fig. 8 is a detail side elevation similar to Fig. 6 is a mop head provided with a modified squeegee, and a different arrangement of the mop material.

Fig. 9 is a sectional plan of the squeegee plate on line 9-9 of Fig. 7.

Referring to the drawing, my squeegee mop consists of a mop stick 11 on which is fastened near its middle portion a hand grip 11a. To

the lower end of mop stick 11 a mop head is fastened, which consists of a metallic rod 12 bent into a T shaped yoke. The horizontal bar of the T forms a flat loop and the vertical end portions, lying side by side close to each other, form a stem 12a. (See Fig. 7). The stem 12a is held within an axial aperture in the lower end of mop stick 11 which is preferably capped by a ferrule 13.

The mop material consists preferably of rope-like strands 20 which are threaded through the opening of the loop 12 to lie side by side of each other. The mop strands are preferably folded upon themselves at their middle portion and around the upper bar 12c of loop 12. They extend upward along mop stick 11 and their free ends are tied by tie wires 14 to a tubular, preferably wooden sleeve 15 which is mounted to slide on mop stick 10 and is provided with encircling grooves into which the mop strands 20 are pressed by means of tie wires 14.

The mop stick 11 carries below the hand-grip 11a the U-shaped wire spring 16 which has one leg rigidly driven into the mop stick, while the other leg is loosely mounted to move transversely in an aperture of mop stick 11.

The curved portion of spring 16 which extends lengthwise of mop stick 11 engages the inner face of tubular sleeve 15 and holds this sleeve tied to mop stick 11 by friction when the mop material is stretched as shown in Fig. 1.

The loop 12 at the lower end of the mop carries below the mop cords 20 which pass therethrough a rectangular squeegee plate 21 of pliable material, preferably rubber. The rounded end portions of loop 12 pass through apertures in plate 21 and the horizontal bar 12b of loop 12 presses this plate tightly against the mop strands 20 and the parallel upper loop portion 12c. Squeegee plate 21 is considerably thicker transversely in its middle portion and chamfered down towards its longitudinal edges as shown in Fig. 6. This construction makes the plate glide smoothly on a floor and avoids shattering in operation.

In Fig. 8 I have shown a modified form of squeegee which is fastened in the above described manner to yoke 12 and consists of a

length of rubber tubing or hose pressed flat by the bars 12b and 12c between which it is clamped.

In this modified form all mop strands extend upward along only one side of mop stick 11, they are threaded through the looped yoke 12 and are clamped between bars 12b and 12c but are cut off close to these bars and their ends unravelled so that they form a soft brush 10 above the squeegee plate.

The operation of my squeegee mop is made clear by the different positions illustrated in Figs. 1 to 5. In Fig. 1 the device is shown when arranged solely for squeegee operation.

15 In this case the mop strands are stretched fan shape along the sides of mop stick 11 and held in that position by means of the frictional engagement of spring 16 with sleeve 15.

In Fig. 2 the device is shown in use for 20 mopping a floor. In this case the squeegee plate is enveloped by the mop material. The rubber plate within the mop material distributes the applied pressure resiliently over a greater floor area than in ordinary mops 25 which improves the mop action considerably.

In Figs. 3 and 4 the device is shown when in use for using squeegee and mop simultaneously. Plate 21 pushes the water on the floor ahead of it and the mop material absorbs it, particularly beyond the ends of plate 21 where the mop is wider than the plate as indicated by arrows a—a in Fig. 4. The mop may also be reversed on the floor so that the stick 11 assumes the direction shown in Fig. 35 2, then the mop material is in front of the plate 21 and is pushed ahead of it absorbing water before it reaches the squeegee plate and by reaction therefrom.

Fig. 5 shows the device in position for 40 wringing. For this purpose the mop cords are twisted about each other and about mop stick 11 by turning the sleeve 15 on the mop stick.

From the above description it will appear 45 clearly that my squeegee mop is very useful and efficient device which reduces the labor of cleaning floors very considerably and by the combined action of mop and squeegee does the work more thoroughly than 50 when they are used individually.

The mechanical construction of the mop is of such simple nature that this improved device can be made and sold for a very reasonable price which in itself constitutes an 55 advancement of the art. However, while a preferred and a modified construction of the invention has been described herein, it shall be understood that other modifications may be made in the design and arrangement of 60 parts and in the construction of minor details as may come within the scope and spirit of the invention as claimed.

Having thus described my invention what I claim as new and desire to secure by Letters 65 Patent is:

1. The combination with a mop stick of a tubular sleeve slidably and rotatably mounted thereon, of a yoke at the lower end of said stick, comprising a bar forming a loop having parallel portions and a longitudinally divided stem thereon, having together the shape of a T, mop material having one end clamped between the parallel portions of said yoke within said loop, the other end being fastened to said sleeve the looped portion of said bar providing means for spreading said mop material into a flat layer close to the lower end of said mop stick and extending upwardly therefrom to form a layer of mop material on said sleeve. 75

2. The combination with a mop stick having a tubular sleeve slidably mounted thereon of a rigid yoke at the lower end of said stick consisting of a bar, shaped to form a loop having parallel straight sides transversely to said mop stick, mop material passing through said loop clamped thereby into a flat layer, at one end and having its opposite end fastened to said sleeve and yielding means on said mop stick spaced from said yoke engaging said sleeve by friction and holding said mop material in stretched position. 85

3. A mop comprising, a mop handle, a flexible squeegee plate fixed to the end of said handle, said squeegee plate having parallel working edges at opposite sides of said handle, and mop material having a portion thereof interposed between said squeegee plate and the end of said mop handle. 95

4. A mop comprising, a mop handle, a flexible squeegee plate fixed to the end of said handle, and mop material interposed between said squeegee plate and the end of said mop handle, and wringing means, to which said mop material is attached, joined to said handle. 105

5. A mop comprising, a mop handle and mop material thereon, a yoke at the lower end of said handle, a flexible squeegee plate held thereby, one end of said mop material being fastened to said yoke, and a tubular sleeve slidably and rotatably mounted on said handle having the other end of said mop material fastened thereto, said sleeve forming means 110 for wringing said mop material. 115

6. A mop comprising, a mop handle, a squeegee plate, stiffening means for said plate fastening it to one end of said handle, a sleeve slidably mounted on said handle, and mop material having one end thereof secured to said sleeve and the other end secured to the end of said handle at said squeegee plate. 120

7. In a mop handle, a supporting means attached to one end of said handle having portions perpendicular to said handle, a flexible plate held by said supporting means, a sleeve slidably mounted on said handle, mop material having one end secured to said support. 125 130

ing means and its other end fastened to said sleeve, for alternately stretching said mop material along said handle and to place it upon said flexible plate.

5 Signed at Brooklyn, in the county of Kings and State of New York, this 30th day of August, A. D. 1929.

HARRY HERTZBERG.
